UNITED STATES PATENT OFFICE

2,473,557

DAVIT

Morgan L. Woodruff, Waban, Mass.

Application April 28, 1947, Serial No. 744,485

18 Claims. (Cl. 9—39)

1

This invention relates to davits for landing and launching boats and it has for its object to provide an improved davit of simple, inexpensive and efficient construction by means of which a boat may be transferred with ease and dispatch from the water to a larger vessel or other support and held securely in position upon the latter while not in use, and by means of which the boat can, with ease and dispatch, be returned to the water.

It is also the object of the invention to provide a davit by means of which a boat may be transferred by a rolling motion thereof from a right-side-up position in the water to an up-side-down position upon a larger vessel or other support, and by means of which the boat may be transferred by a reverse rolling motion thereof from an up-side-down position upon the vessel or other support to a right-side-up position upon the water.

To these ends I have provided an improved davit apparatus for attachment to a vessel or other support and which, in the preferred embodiment of the invention, may be constructed and operate as set forth in the following description, the several novel features of the invention being particularly pointed out and defined in the claims at the close of the description.

In the accompanying drawings:

Figure 1 is a side elevation of the stern end of a relatively large vessel equipped with a davit apparatus constructed in accordance with this invention and showing a relatively small tender or dinghy right-side-up upon the water adjacent thereto.

Figure 2 is a view like Figure 1 but showing the small boat fully raised out of the water and supported horizontally by the davit apparatus in an up-side-down position where it is securely fixed as will appear later.

Figures 3 and 4 are details illustrating the operation of the davit apparatus.

Figure 5 is a plan view of the parts shown in Figure 2.

Figure 6 is a rear elevation of the parts shown in Figure 1 but with the smaller boat or tender and the operating cable removed.

Figure 6a is a section on line 6a—6a of Fig. 6b showing the deck cleat hereinafter described.

Figure 6b shows the elements of 6c as viewed in the direction of the arrow (Fig. 6c).

Figure 6c shows the deck cleat and a portion of the gunwale of the small boat or tender as viewed from within the larger vessel.

Figure 7 shows, partly in elevation and partly

2

in section, the cross-bar portion of the bail-shaped lever hereinabove described.

Figure 8 is a rear elevation, partly in section, of a portion of one of the legs or tines of the bail-shaped lever and its supporting fork.

Figure 8a is a section on line 8a—8a of Fig. 8.

Figure 9 is a section on line 9—9 of Figs. 5 and 10.

Figure 10 illustrates the manner in which the tender or smaller boat is tied to the deck cleat of the larger vessel.

In the drawings 13 represents the stern end of a relatively large vessel which is provided with a pair of spaced-apart rearwardly extending cantilever arms 11, 11, each of which is provided at its rear end with a fork 12 within which is disposed the intermediate portion of one of the two arms or tines of a bail-shaped lever that is indicated generally at 14, (Figs. 1, 2, 5 and 6), the upper ends of said arms being connected by a composite cross-bar 15 that is shown in Figs. 6 and 7.

Each arm 13, 13, includes, as a part thereof, a tubular metallic section 16 having a straight end portion pivotally secured within its fork 12 by means of a pivot pin 17 (Figs. 8 and 8a) and into this straight end portion is telescopically fitted one end of a stem 18 that is provided at its outer end with a V-shaped yoke 19 (Figs. 1 to 6, inclusive). The opposite end portions of the tubular sections 16 are curved inwardly toward each other and have fitted telescopically into the same the opposite ends of a pintle 20 (Fig. 7) on which is rotatably mounted a sheave 21 disposed between the proximate ends of the sections 16. One end of pintle 20 is fastened within its section 16 by means of a taper pin 22 driven into registering apertures provided through said section and the pintle, while the opposite end of the pintle is fastened within its section 16 by the shank of a keeper 23 that is cooperatively associated with the sheave 21, said shank being driven into registering apertures provided in said section and the pintle.

The end portion of each stem 18 which is telescopically fitted into its section 16 is made with a longitudinal series of transverse apertures 23' (Figs. 8 and 8a) that are uniformly spaced apart a distance equal to the distance between the pin 17 and a pintle 24. One or the other of the apertures 23' is occupied by the pin 17 and another by the short pintle 24 whose opposite ends occupy apertures provided in the section 16.

The series of apertures 23' is provided so that when pin 17 is removed the stem 18 and sec-

tion 16 may be adjusted relatively to shorten or lengthen the arm of the bail-shaped lever 14 of which they are parts, the pintle 24 remaining in place and holding said parts together while this adjustment is being made, or if necessary, being transferred to another aperture 23 to permit the desired adjustment being made.

The pivot pin 17 is preferably so disposed relatively to the center of gravity of the lever structure that when the latter is free of control it is held by gravity in the vertical position shown in Figs. 1 and 6 where its movement toward that position is limited by the crotches of forks 12, as shown in Fig. 8a. Thus the bail-shaped lever 14 is pivotally supported by the forks 12 so that it can be swung back and forth between the vertical position shown in Fig. 1 and the horizontal position shown in Fig. 2.

As shown particularly in Fig. 6 each yoke 19 comprises a top cross-bar 25 to the middle of which is welded or otherwise fixed the outer end of the stem 18 and to the outer ends of cross-bar 25 are welded or otherwise fixed the upper ends of two side-bars 26 which extend longitudinally and convergently from said cross-bar 25 with their outer ends fitted against and welded or otherwise secured to the opposite ends of a rung 27. As shown in Figs. 1 and 6 these yokes are disposed at a predetermined distance above the water level W for a reason that will presently appear.

The tender or dinghy 28 provided for use with my new davit has rigidly fixed in position upon the top of its gunwale at one side thereof two outwardly facing hooks 29, 29, (Figs. 1, 2 and 5) which are spaced apart the same distance as are the yokes 19, 19, while a single outwardly facing hook 30 is fixed in position upon the top of the gunwale at the opposite side of the tender 28, said single hook being disposed about midway between the two hooks 29, 29, when viewing the tender horizontally from one side thereof.

The gunwale of the tender 28 is herein shown as provided upon its exterior and at the top with an outwardly extending flange or bead 31 (Fig. 1) and the same screws by which the single hook 30 is fastened to the top side of the gunwale serve also to fasten a cleat 32 in position upon the exterior of the gunwale and against the bottom side of bead or flange 31 as shown in Figs. 1, 6b, 6c, 9 and 10.

The tender 28 is rolled from its position in the water (Fig. 1) and landed aboard the vessel 10 as shown in Fig. 2 through the manual operation of a cable 33 by an individual on board of said vessel. One end of this cable is made fast to an arm 34 (Figs. 1, 6, 7, 9 and 10) welded or otherwise fastened to the upper end of one of the sections 16 of the cross-bar of the bail-shaped lever 14 and from this arm the cable extends over the sheave 21 and thence aboard the vessel 10. Preparatory to the use of the cable 33 the tender 28 is placed in position opposite the stern of vessel 10 where it is disposed transversely relatively to the latter with the side thereof on which the pair of hooks 29 are mounted nearest said vessel as shown in Fig. 1. The portion of cable 33 between sheave 21 and arm 34 is then formed into a loop 33' which is engaged with the single hook 30 as shown in Fig. 1, whereupon the operator aboard vessel 10 pulls in upon the cable and thereby warps the tender into the position indicated by dotted lines at a (Fig. 1) where the pair of hooks 29 are opposite the upper larger ends of the yokes 19. Thereafter continued pull upon cable 33 tips the

tender sidewise (Fig. 3) causing the gunwale that is against the yokes 19 to slide downwardly against the latter which swings the hooks 29 into the yokes whose converging sides direct the hooks onto the rungs 27 (Fig. 4). After engagement of the hooks 29 with the rungs of the yoke 5 continued pull upon the cable first swings the tender pivotally upwardly on said rungs into the position indicated by dotted lines at b in Fig. 1 after which the bail-shaped lever 14 is swung pivotally on the pivot pins 17 (Figs. 1, 2 and 8) into the horizontal position shown in Fig. 2 carrying the tender with it.

As the tender 28 arrives in the position shown in Fig. 2 its single hook 30 (Figs. 1, 6a, 6b and 6c) enters a socket 35 forming part of a cleat 36 fixed in position upon the top of a stern deck 37 of the vessel 10 whereupon the cable 33 is wrapped back and forth around the two cleats 32 and 36 (Figs. 9 and 10) to secure both the tender and the bail-shaped lever in the positions shown in Fig. 2. Thus secured in position the engagement of the hook 30 with the socket 35 serves to hold the pair of hooks 29 in engagement with the rungs 27 of the yokes 19 and the latter, together with the socket 35, serve to hold the tender against displacement transversely relatively to the vessel 10.

In launching the tender 28 the cable 33 is disengaged from the cleats 32 and 36 whereupon the lever 14 is shifted into the position shown in Fig. 1 with the tender 28 occupying the position shown at b. Slack being now given to cable 33 the tender will swing under the influence of gravity downwardly into the water as indicated by dotted lines at a so that when the loop 33' is disengaged from the single hook 30 the tender is free for use.

Among the advantages to the above described construction I would point out that all operations connected with either launching or landing the tender can be performed from the cockpit of the larger vessel without getting into the tender at all; during these operations only about twenty-five per cent of the weight of the tender or dinghy is imposed upon the operator; said operations can be carried out with ease and dispatch owing to the lightness of the effective weight of the tender or dinghy, and the dinghy or tender can enter the water in no other way than right-side-up so that it cannot fill or swamp and floats free, the hooks being floated out of the yokes.

What I claim is:

1. A davit apparatus for launching and landing a boat comprising a lever structure; means for pivotally supporting said lever structure intermediate its opposite ends upon a support at a point above the level of a body of water with provision for angular movement thereof on a horizontal axis to and from an upright position above said water alongside said support and to and from an approximately horizontal position where one end portion thereof overlies said support; means disposed adjacent to the lower end of said lever structure when the latter occupies its upright position for pivotal interlocking engagement with one side of the boat; means under the control of an operator stationed upon said support engageable with the opposite side of the boat and operable to hold said first-mentioned side of the boat against and interlocked with said lower end while utilized to swing said boat upwardly on said interlocking means into position alongside said lever structure and to thereafter swing said lever structure and boat on said axis into approximately horizontal positions with the boat resting up-side-

down on said lever structure, and means for co-operating with said operator-controlled means to releasably secure said lever structure and boat to said support in said last-mentioned position.

2. A davit apparatus for launching and for landing a boat, said apparatus comprising a lever structure; means pivotally connecting said lever structure intermediate its opposite ends to a support to swing on an axis that is parallel with and above the level of a body of water, said lever structure being angularly adjustable on said axis to and from an upright position alongside said support and to and from an approximately horizontal position where one end portion thereof overlies said support; means on said lever structure that is disposed adjacent to the lower end thereof when said lever structure occupies its upright position for pivotal interlocking engagement with one side of the boat; means under the control of an operator stationed upon said support that is engageable with the opposite side of the boat and operable to hold said first-mentioned side of the boat against and pivotally interlocked with said lower end of said lever structure while it is operated to swing said boat upwardly on said means for pivotal interlocking engagement into position alongside said lever structure and to thereafter swing said lever structure and boat on said axis into approximately horizontal positions with the boat resting up-side-down on said lever structure, and means for co-operating with said operator-controlled means to releasably secure said lever structure and boat to said support in said last-mentioned position.

3. A davit apparatus comprising a lever; means pivotally connecting said lever intermediate its opposite ends to a relatively large vessel to swing on an axis that is parallel with and above the level of the water supporting said vessel, said lever being angularly adjustable on said axis to and from an upright position alongside said vessel and to and from an approximately horizontal position; a pair of horizontally spaced-apart yokes carried by the end of said lever that is lowermost when said lever occupies its upright position; a tender for said vessel provided at one side thereof with a pair of horizontally spaced-apart elements to pivotally interlock with said yokes; a cable under the control of an operator stationed upon said vessel, said cable being engageable with the opposite side of said tender and operable to urge said first-mentioned side of the tender against said yokes and thereafter to roll the tender upwardly into position alongside said lever thereby pivotally interlocking said elements with said yokes and urging said lever toward its approximately horizontal position, and cleats on said tender and vessel with which said cable is engaged to separably fasten said lever in its approximately horizontal position with the tender fixedly but separably secured thereon in an upside-down position by said cable and the interlocked elements and yokes.

4. A davit apparatus according to claim 3 wherein each of said elements is an outwardly facing metal hook provided on the gunwale of the tender, and wherein each yoke is V-shaped and provided at its smaller end with a transverse rung to be engaged by one of said hooks.

5. A davit apparatus according to claim 3 wherein a sheave is rotatably mounted upon the end of said lever that is uppermost when said lever occupies its upright position, wherein said cable extends from said vessel over said sheave and is anchored at its one end to said uppermost end of

said lever, wherein a bracket is provided upon said opposite side of the tender, and wherein a loop formed in said cable between said anchorage and said sheave is separably engaged with said bracket through which it is reeved when said cable is operated.

6. A davit apparatus according to claim 5 wherein the cleat that is provided on the vessel is made with a socket that is occupied by said bracket when said lever occupies its approximately horizontal position thereby to secure said tender against lateral displacement.

7. A davit apparatus according to claim 3 wherein said lever is U-shaped, wherein each arm of said U-shaped lever is pivotally connected with said vessel and made in two telescopically associated sections that are adjustable relatively to vary the length of the arm, and means is provided for fixing said sections in their adjusted relationship.

8. A davit apparatus comprising a U-shaped lever having its intermediate portion disposed horizontally and equipped with a rotatable sheave; means pivotally connecting said lever intermediate its opposite ends to a relatively large vessel to swing on an axis that is parallel with and above the level of the water supporting said vessel, said means comprising a pair of cantilever arms fixed to said vessel each of which is provided at its outer end with a fork within which the intermediate portion of one of the arms of said lever is pivotally mounted with the crotch of at least one of said forks serving as a stop to limit the movement of the lever toward an upright position, said lever being angularly adjustable on said axis to and from said upright position alongside said vessel and to and from an approximately horizontal position; a pair of horizontally spaced-apart yokes carried by the end of said lever that is lowermost when said lever occupies its upright position; a tender for said vessel provided at one side thereof with a pair of horizontally spaced-apart elements to pivotally interlock with said yokes; a cable fastened at its one end to the intermediate portion of said lever, said cable being under the control of an operator stationed upon said vessel and extending from said vessel over said sheave and being engageable with the opposite side of said tender and also operable to urge said first-mentioned side of the tender against said yokes and thereafter to roll the tender upwardly into position alongside of said lever thereby pivotally interlocking said elements with said yokes and swinging said lever into its approximately horizontal position, and cleats on said tender and vessel with which said cable is engaged to separably fasten said lever in its approximately horizontal position with the tender fixedly but separably secured thereon in an upside down position by said cable and the interlocked elements and yokes.

MORGAN L. WOODRUFF.
